(57) **CLAIM**

The ornamental design for a toddler chair, as shown and described.

DESCRIPTION

FIG. 1 is a perspective view of the toddler chair according to the present design;

FIG. 2 is a left side view of the toddler chair of FIG. 1;

FIG. 3 is a right side view of the toddler chair of FIG. 1;

FIG. 4 is a front side view of the toddler chair of FIG. 1;

FIG. 5 is a back side view of the toddler chair of FIG. 1;

FIG. 6 is a top side of the toddler chair of FIG. 1; and,

FIG. 7 is a rear side view of the toddler chair of FIG. 1.

The broken lines illustrate the environment and form no part of the claimed design.

1 Claim, 7 Drawing Sheets
